UNITED STATES PATENT OFFICE

JAMES E. HESTER, OF PITTSBURGH, PENNSYLVANIA

CLOTHESLINE SUPPORT

Application filed May 9, 1929. Serial No. 361,744.

This invention relates to clothes-line supports and, while not limited thereto, relates more particularly to clothes-line supports adapted to be attached to a post, building or other supporting structure, and has for its object the provision of a clothes-line support that is readily adjustable vertically so as to facilitate the attachment of the line and so that the line may be elevated either before or after the clothes are hung thereon and avoid the necessity of using intermediate temporary supports along the line.

In the drawings—

Figure 1 is a front elevation of a support constructed in accordance with my invention.

Figure 2 is a side elevation thereof, showing the support attached to a building.

Figure 3 is a transverse sectional view taken on the line III—III of Figure 2.

Figure 4 is a similar view showing the support clamped on a standard metal post.

Figure 5 is an enlarged side elevation of the body portion of the support.

Figure 6 is an enlarged front elevation thereof.

Figure 7 is an enlarged side elevation opposite that of Figure 5.

Referring more particularly to the drawings, the letter A designates the body member 30 as a whole which is preferably of elongated box-like construction and is formed from a single piece of metal cut and pressed up to form a back wall 2 and side and end walls 3 and 4, respectively. The end walls 3 will 35 preferably overlap the end faces of the side walls 2 and the abutting faces of the end and side walls may be welded or otherwise secured together, if desired.

The side walls 2 have their forward edges 40 cut away at vertically spaced intervals to form notches 5 which have their bottom walls convexly recessed, as at 6, said notches being for a purpose to be described.

The end walls 3 are provided with aligned 45 apertures 7 in which are fixedly mounted bushings 8.

A two-piece tubular line supporting standard of more than twice the length of said body is composed of tubular sections 9 and 10, 50 of substantially equal length which are

joined together by a T-fitting 12. The sections 9 and 10 are loosely mounted through the bushed apertures in the top and bottom end walls, respectively, of the body member A so as to have a sliding and revolvable fit therewith and are then joined by the T-fitting.

A handle member 14 is secured in the intermediate arm of the T-fitting and projects outwardly at right angles to the standard member.

The upper end of the supporting standard is provided with a cap member 15 having an eye 16 thereon in which a hook 17 is linked so as to have a swinging connection.

The body member A is provided with a plurality of apertures 18 through which bolts, screws, nails or other fastening members 18^a are driven to secure the body to a post, building wall or other structure indicated at 19.

When the device is to be fastened to a post such as indicated at 20 in Figure 4, U-clamps 21 or other clamping members may be used.

In operation, the line support 19 is adapted to be lowered until its handle 14 will enter the lowermost notch 5 and the handle and support will then be rotated and the handle entered in the lowermost notch and seated in the recess 6 of said notch. The line may then be readily attached to the hook 17. After the line has been attached to the support, the support may be readily raised by lifting on the handle 14 and moving it up to one of the other successively higher notches. If, after the clothes are hung on the line, they are too close to the ground the support may be further elevated by lifting on the handle 14 and raising to a still further notch.

By providing the notches 5 in both side walls 3 the device is capable of either right or left hand operation and, therefore, is of universal application. If a closer spacing of notches is desired, the notches in one side wall may be staggered relative to the notches in the other wall and then, by entering the handle in the notches of the opposite walls, a close adjustment may be had.

The device above described is of simple construction, cheap to manufacture, has no springs or other delicate mechanism to get

out of order and is of universal application,— that is, it may be readily attached to the side wall of a building, to a pole or to any other permanent structure.

5 While I have shown and described certain specific embodiments of my invention it will be understood that I do not wish to be limited thereto since various modifications may be made without departing from the scope of 10 my invention, as defined in the appended claims.

I claim—

1. A clothes-line support comprising a one-piece, elongated box-like body member having back, side and end walls, said end walls being provided with alined apertures, and said side walls having their forward edges cut away at vertically spaced intervals to form notches, and a line supporting stand- 20 ard having a length greater than twice the length of said body, said standard projecting through said apertures in said end walls and being slidably and revolvably mounted relative to said body, a handle member secured 25 to said standard intermediate the ends thereof and projecting at right angles therefrom, said handle serving to limit the movement of said standard so as to prevent the movement of said standard out of said body, and said 30 handle and said standard being adapted to be rotated so as to move said handle into position to be engaged in selected ones of said notches to support said standard at various selected vertical positions.

35 2. A clothes-line support comprising a one-piece, elongated box-like body member having back, side and end walls, said end walls being provided with alined apertures, and said side walls having their forward 40 edges cut away at vertically spaced intervals to form notches, and a two-piece tubular line supporting standard having a length greater than twice the length of said body, said standard projecting through said apertures 45 in said end walls and being slidably and revolvably mounted relative to said body, said standard being divided at a point approximately midway between its ends and the two parts thereof being joined by a T-fitting, a 50 handle member secured in said T-fitting and projecting outwardly at right angles to said standard, said handle and said standard being adapted to be rotated so as to move said handle into position to be engaged in selected ones of said notches to support said standard 55 at various selected vertical positions.

3. A clothes-line support comprising a one-piece, elongated box-like body member having back, side and end walls, said end walls being provided with alined apertures, and said side walls having their forward edges cut away at vertically spaced intervals to form notches, said notches having their bottom walls cut out to form concave recesses, 65 bushing members fixedly mounted in said ap-

ertures, and a two-piece tubular line supporting standard having a length greater than twice the length of said body, said standard projecting through said bushings in 70 said apertures in said end walls and being slidably and revolvably mounted relative to said body, said standard being divided intermediate its ends and the two parts thereof being joined by a T-fitting, a handle member secured in said T-fitting and projecting outwardly at right angles to said standard, said handle and said standard being adapted to be rotated so as to move said handle into position to be engaged in selected ones of said notches to support said standard at various 75 selected vertical positions.

4. A clothes-line support comprising a one-piece, elongated box-like body member having back, side and end walls, said end walls being provided with alined apertures, a bush- 80 ing in at least one of said apertures, at least one of said side walls having its forward edge cut away at vertically spaced intervals to form notches, and a two-piece tubular line supporting standard having a length greater 85 than twice the length of said body, said standard projecting through said apertures in said end walls and being slidably and revolvably mounted relative to said body, said standard being divided at a point approxi- 90 mately mid-way between its ends and the two parts thereof being joined by a T-fitting, a handle member secured in said T-fitting and projecting outwardly at right angles to said standard, said handle and said standard being adapted to be rotated so as to move said handle into position to be engaged in selected ones of said notches to support said standard 95 at various selected vertical positions.

In testimony whereof I have hereunto set 100 my hand.

JAMES E. HESTER.
